DRINK MIXER OR THE LIKE

James M. Ferris, 120 N. Center St., Canton, Pa.

Filed Oct. 5, 1965, Ser. No. 87,317

Term of patent 14 years

(Cl. D44—1)

FIG. 1 is an elevational view of a drink mixer or the like showing my new design; and

FIG. 2 is a top plan view thereof, the bottom plan view being similar.

I claim:

The ornamental design for a drink mixer or the like, as shown and described.
